UNITED STATES PATENT OFFICE.

LEWIS S. DAVIS, OF NEW PARIS, OHIO.

BLOCK FOR HORSE-COLLARS.

Specification of Letters Patent No. 10,502, dated February 7, 1854.

To all whom it may concern:

Be it known that I, LEWIS S. DAVIS, of New Paris, Preble county, Ohio, have invented a new and useful Expanding Block 5 for Horse-Collars; and I do hereby declare the following to be a full, clear, and exact description thereof, reference being had to the annexed drawings, making part of this specification.

10 The object of my invention is such a construction of the block on which a collar is formed and stretched as shall, firstly, adapt it to every size of collar, and, secondly shall entirely supersede the use of the mallet in 15 stretching the collar.

In the accompanying drawings Figure 1 is a side elevation of my block Fig. 2 is a top view, the cap being removed.

(a) is a base board, having affixed at its 20 center, in a vertical position, a bolt (b) which serves as the fixed bearing and support for the right and left hand screw (c), and also for the cap (d), and prevents their longitudinal displacement as hereafter explained. The block is disposed around the 25 fixed bolt (b), and is divided into four sections (e e' f f') by two vertical joints, of which, one extends from neck to gullet of the block, (dividing it into two equal and 30 similar halves) and the other crosses the block at its greatest width, at right angles to the former one. The two front sections and the two back sections are hinged together in pairs, the former at the gullet and 35 the latter at the neck of the block. These hinges, while holding them together at their front and rear edges, permit their divergence at the transverse joint, so as to increase the bilge of the block, and thus give 40 a greater width to the collar which is to be formed upon it. This divergence is made to occur simultaneously with and in a certain fixed proportion to, the extension lengthwise of the block by the following 45 means. The right and left hand screw (c) has at its midlength a collar, see dotted lines (c') working within a yoke (b') on the vertical bolt (b).

The nuts (g g') of this screw occupy 50 niches in their respective sections, so that on the rotation of the screw, the front and back portions of the block, are caused to recede from or to approach each other; and at the same time, their divergence or convergence widthwise, is effected by means of 55 the inclined grooves (h h' i i') in the base,

and similar ones in the cap (d); the said grooves being occupied by pins (k k' l l') on the top and on the bottom of the block, one pin occupying the top and another the 60 bottom of each section. The grooves operating on the forward pins, diverge more rapidly than the others, in order to effect a greater proportional enlargement of the front portion of the block; and thus preserve the proper shape, for it will be evident on inspection, that where the block is very much prolonged, the front ends of the back sections are some distance behind the 65 bilge of the collar and do not therefore require so great an enlargement as the front 70 sections.

(m m') are two strips of sheet steel, which being attached to the front sections, overlap the front edges of the rear ones, and cover 75 the gap left by the separation of the front and back portions, when the block is expanded; and thus preserve a continuous surface at this part. These strips I call the 80 sheaths.

The application of my block, will be evident to every collar maker.

The bag being soaked and properly stuffed, is slipped over the block in a contracted condition, and the screw being applied, "the stretch is taken out", and the desired form and size is given; upon which the collar, after being allowed a short time to take its set, is removed and the block is again contracted for the reception of another collar.

The customary process of blocking a collar, namely, slipping it over the top of a block and beating it down with repeated blows of a mallet and driver, is not only a 95 comparatively tedious one, but is less exact in its operation, and even in practised hands the collar is more or less liable to injury by the action of the mallet. The block also in course of use always gets battered and 100 splintered by the mallet, and the smaller class of collars being forced over these splintered surfaces become chafed and frayed.

By means of my device, a collar may be 105 formed and stretched with more accuracy and shapeliness, less detriment to the collar, and in one tenth part of the time ordinarily necessary; and by moving the screw to a set distance each time, a number of collars may 110 be formed of exactly corresponding size.

I do not claim as novel, the construction

of a horse collar block in expanding sections, but

I claim herein as new and desire to secure by Letters Patent—

- 5 The four parted collar block, of which the front pair of sections are hinged together at the gullet, and the back pair, at the neck of the block as described; the same being combined with a stationary bolt (b), placed at 0 the intersection of the partings, the said bolt serving to unite the base and cap, and also forming a fixed bearing for the right and

left hand screw (c), which in conjunction with the pins on the block, and the diverging grooves in the base and cap, effect the prolongation and proportional lateral expansion of the block; or devices substantially equivalent. 15

In testimony whereof, I hereunto set my hand before two subscribing witnesses.

LEWIS S. DAVIS.
